PATENTED MAY 31, 1904.

M. MUNTADAS Y ROVIRA.

APPARATUS FOR TREATING FABRICS.

APPLICATION FILED AUG. 11, 1903.

NO MODEL.

UNITED STATES PATENT OFFICE.

MANUEL MUNTADAS Y ROVIRA, OF BARCELONA, SPAIN.

APPARATUS FOR TREATING FABRICS.

SPECIFICATION forming part of Letters Patent No. 761,107, dated May 31, 1904.

Application filed August 11, 1903. Serial No. 169,140. (No model.)

To all whom it may concern:

Be it known that I, MANUEL MUNTADAS Y ROVIRA, a subject of the King of Spain, residing at Barcelona, in the province of Barcelona 5 and Kingdom of Spain, have invented certain new and useful Apparatus for Treating Fabrics; and I do hereby declare the following to be a full, clear, and exact description of the invention, such as will enable others skilled in 10 the art to which it appertains to make and use the same.

My invention relates to improvements in apparatus for continuously bleaching, steaming, and washing fabrics and yarns; and the object of my invention is to provide an apparatus whereby the above operations are carried on in a methodical and systematic order, which results in the saving of space, time, and labor and greatly increases the efficiency of 20 the work. With this object in view it may be understood that, first, a "methodical washing" is that in which the water circulates in a reverse direction to that of the fabric to be washed, so that the cleanest one is in contact 25 with the cleanest water and the most soiled fabric is in contact with the impurest water; second, a "methodical lixiviation" is that in which the lye circulates in a reverse direction to that of the fabric to be lixiviated, so that 30 the fabric not yet lixiviated enters the less pure or less alkaline lye and issues from the most alkaline and purest one; third, a "methodical steaming" is that in which the cleanest fabric is in contact with the steam of highest pressure and the most soiled fabric is 35 in contact with the steam of lowest pressure.

The objects of my improved apparatus are:

First. To subject the fabrics or yarns forming a chain to the action of steam and lye in 40 such a manner that when moving forward they come in contact with portions of successively-purer lye and with steam of successively-higher pressure. This result is obtained by means of chambers having inner walls or partitions between which liquid joints or seals are formed by the same lye which flows from 45 one chamber to the other. The lye permits the fabric to pass free; but it does not permit the escape of the steam contained in said chambers. Several chambers may be arranged for

the lye to pass through from one another until it is exhausted, and the steam may have a different pressure in each, so that the former chamber is at the lowest and the latter at the highest pressure.

55

Second. To subject the fabrics or yarns to the action of the steam alone after lixiviation, this being obtained by forcing the fabric to pass through a chamber containing steam at an equal or higher pressure than that of the 6c last lixiviation-chamber.

Third. To subject the fabrics or yarns to the alternative action of the water and steam by forcing them to pass through several chambers separated from each other by inner walls 65 or partitions, forming water-joint between them by means of the same washing-water. The fabric enters the water by the most soiled portion thereof and emerges from the same by the purest portion of it. The former 7c chamber contains the steam at the highest pressure and the final one contains it at the lowest pressure. The lye is conveyed by a pipe from one chamber to the other, and the water passes from one chamber to the other 75 by means of any preferable device or apparatus. The difference between the steam pressure in the several chambers is regulated by the height of the inner walls or partitions forming the water joints or seals, so that each 80 liquid column is sufficient to balance the pressure in the next chamber.

In the accompanying drawings, Figure 1 is a vertical longitudinal section of my improved apparatus. Fig. 2 is a horizontal cross-section 85 thereof, and Fig. 3 is a cross-section showing the means for supplying the washing liquid from one chamber to another.

Referring to the drawings, my improved apparatus consists of a large casing open at the 90 top, having end walls *a* and a bottom *b* secured thereto. In the interior of this chamber rise from the bottom thereof partitions *c*, *d*, *e*, *f*, *g*, *h*, and *i* of the same height as the end walls *a*. Similar partitions *j*, *k*, *l*, *m*, *n*, *o*, *p*, and *q* are 95 also provided. These partitions are arranged alternately in respect to the partitions before mentioned and are of less height than said first-named partitions. Into this casing projects downwardly a second casing slightly smaller 100

than the first, which is provided with a closed top *r* and end walls *s*. This second casing is open at the bottom, and from the top of said casing depend vertical partitions *t*, *u*, *v*, *w*, *x*, 5 and *y*, which are arranged close to the partitions *c*, *d*, *e*, *f*, *g*, and *h*, but without touching them. These partitions do not reach down into the bottom of the main casing, but are separated from it by a considerable space, 10 and the casings are secured in their proper relative positions with relation to each other by any desired means. The interior of the smaller casing is thus divided into a number of chambers 1, 2, 3, 4, 5, 6, and 7, each of 15 which has an opening near the bottom and the central one of which, 4, is considerably larger than the others. The chambers 1, 2, and 3 are also considerably larger than the chambers 5, 6, and 7 in order to afford space 20 for the looping devices 8, which are of the ordinary type. The chambers 1, 2, and 3 are designed for the reception of a bleaching agent, and the chambers 5, 6, and 7 are designed for the reception of a washing agent, 25 and steam under pressure is admitted into each one of these chambers, but at a different pressure, the pressure in the chamber 2 being greater than that in the chamber 1, and so on, increasing until the chamber 4 is reached, in 30 which the maximum pressure of steam is maintained, and then decreasing by successive gradations in the chambers 5, 6, and 7.

9 represents a fabric passing through the several chambers successively, through the 35 bleaching agent, and through the washing agent, being subjected to steam-pressure at times. In case it is desired to treat yarns they are put on cross-bars arranged on an endless chain and conveyed through the apparatus 40 in the same way as the fabric 9. The fabric or yarns pass over rollers 10, arranged near the top and bottom of the apparatus. By means of the folders 8 the fabric is folded into the space between the partitions 11 in the usual 45 manner.

12 represents a steam-pipe running from a suitable source of supply and having a branch pipe connected with the several chambers. On each branch pipe is a pressure-regulator 50 13 and a gage 14, so that the pressure in each chamber may be regulated and observed.

The lye or other bleaching agent is driven by a pump 16 through a pipe 15, which enters the chamber 4 at the point 16 in the lower part 55 thereof. The pressure of steam in the chamber 4 causes a liquid seal to be made around the bottom of the partition *v* and forces the liquid to the top of the partition *e*, from whence it is delivered by a gravity through 60 the pipe 17 into the chamber 3 near the bottom of the partition *u*, where another liquid seal has formed, the liquid rising between the partitions *d* and *u*, but not to the top of the partition *d*, inasmuch as the pressure of steam 65 in the chamber 3 is less than that in the cham-

ber 4, usually by about half an atmosphere. By similar means liquid seals are formed underneath the partitions *s* and *t*, the impure lye passing out through the opening 18, to which a waste-pipe is preferably attached. By this 70 arrangement it will be seen that the fabric or yarns under treatment first pass through the bleaching agent in its foulest condition, then into a chamber under steam-pressure, then into purer liquid, and so on until the material 75 treated passes into the pure bleaching agent, and then into the chamber containing the highest pressure of steam, in which chamber, owing to its size and to the two loopers, the fabric remains longer than in any other of 80 the chambers. The liquid washing agent is delivered into the chamber 19, formed by the partition *i* and end wall *a*. From thence it is pumped by a pipe 20 (see Fig. 3) into the opening 21, from whence it falls down and 85 makes a water seal around the partition *s*. From thence it is pumped through a pipe 22 to a point near the partition *h* into the chamber 7, and as it is delivered from the pipe 22 it forms a water seal around the lower end of 90 the partition *y*. Thence it is pumped through the pipe 23 to a point near the top of the partition *g*, and as it issues from said pipe 23 it falls and forms a water seal around the lower 95 part of the partition *x*. Thence it is pumped through a pipe 24 to a point near the top of the partition *f*, and it then falls and forms a liquid seal around the lower end of the partition *w*, finally being discharged through an 100 opening 25, which leads to a waste-pipe 26. There is a pump connected with each of the 105 pipes 23 and 24, similar to the pump shown at 20 in Fig. 3; but to avoid complication these pumps have not been shown on Figs. 1 and 2. In practice I prefer to have steam under a 110 pressure of about half an atmosphere in the chamber 1, one atmosphere in the chamber 2, one and one-half atmospheres in the chamber 3, two atmospheres in the chamber 4, one and one-half atmospheres in the chamber 5, one 115 atmosphere in the chamber 6, and a half an atmosphere in the chamber 7. In the chamber 1 there is a steam-pressure of half an atmosphere, sufficient to force the liquid up to the 120 overflow-orifice in the small passage through which the fabric is fed in. In the chamber 2 there is a pressure of one atmosphere, which overbalancing the pressure in the chamber 1 by half an atmosphere would cause the liquid in the seal to rise to the same height; but before it gets to that height it runs over into the inclined tube at the top of the liquid seal and is discharged into the lower part of the chamber 1. A similar action takes place in the chambers 3 and 4, so that there is a steady 125 circulation of the liquid, owing to the steam-pressure from the chamber 4 into the chamber 3 through the inclined pipe, from the chamber 3 into the chamber 2, and so on until the liquid is discharged. On the other side 130

of the central chamber 4 a circulation toward the opposite end of the apparatus would naturally take place under the influence of the steam-pressure; but this tendency to circulate is overcome by the positively-actuated pumps, which pump the liquid from the chamber 7 to the chamber 6, from the chamber 6 to the chamber 5, and from the chamber 5 to the chamber 4. Thus the level of the liquid at 10 the top of the liquid seals and at the bottom of the chambers is substantially the same in each of the chambers. In the present case the greatest internal pressure is supposed to be of two atmospheres corresponding to differential pressures of one-half atmosphere between the chambers, so that the level of the seal columns may be of approximately five meters. This arrangement may vary at will by increasing either the number of chambers 20 or the pressure therein; but in this case the level of the seals or columns, and consequently the height of the inner walls or partitions, should be increased. This arrangement offers the following advantages: An apparatus 25 can be constructed in which the fabrics or yarns or other materials may be steamed at a high pressure without necessitating liquid columns of great height (in the present case twenty meters) for balancing the great interior pressure. On the other hand, if we consider the fabric entering on the left and discharging on the right and the liquid of the columns or seals being not water but lye it will be seen that the fabric entering the apparatus 30 is subjected to the action of the lye of progressively-increasing alkalinity and to the action of steam of increasing temperature. The advantages of my improved arrangement are considerable, viz: 35 First. The fabrics do not pass suddenly from the exterior temperature to the high temperature of the central chamber, but the change takes place gradually. Second. Only the dirty and almost completely-exhausted lye is discharged through the overflow of the seal α , and this lye, which should not act at all on the already-lixiviated fabric, does still act on the completely raw fabric and assists the dissolving of the dressing thereof. In known apparatus, on the contrary, the impurities remaining in the lye retard and even prevent the action of said lye. Consequently it is necessary to give the lyes an excess of alkali in order that they will 45 be effective during the latter stages of the operation. Notwithstanding this fact, it is well known that after a certain time the weakening of the lye ceases and that it does not act further in spite of the alkalinity which it still possesses. In all known apparatus that part of the alkali which remains in the lye can be considered as totally lost; but it is not so in the present apparatus, in which the lye flows away completely exhausted. 50 Third. The immersion in the lye and the

intermittent steaming gradually opens the pores of the fiber, and if previous to the immersion in new lye the soap formed is removed the new lye will act under the best conditions for finishing the saponification. 70

Fourth. The intermittent steaming and lixiviation tends to prevent the production of oxycellulose.

Fifth. The great temperature to which this apparatus can be worked makes the action of 75 the lye more energetic than in the known continuous apparatus, as it is a well-known fact that the fiber contains certain impurities which are difficult to saponify under 120° centigrade, but which are easily saponifiable 80 over this temperature.

Sixth. The methodical washing, combined with the intermittent steaming, completely eliminates the products of saponification 85 formed, and the fiber can be immediately chlorinated or dried without further washing.

Seventh. The special arrangement of the steaming-chambers placed in series or parallel permits a light and comparatively weak construction of the apparatus in which the 90 inner pressure is of some atmospheres, as the side walls can be strengthened by stays without any other special arrangement, and, on the other hand, the upper and lower walls can be reinforced by beams constructed as a solid 95 body of equal resistance.

My improved apparatus, as compared with the Walter apparatus, presents the following advantages and differences: It may be of much smaller dimensions for an equal production. In 100 said Walter apparatus the fabric is subjected only to one immersion in the lye and to a single steaming for a long time, while in the present apparatus the immersions are intermittent and always increasing from the former 105 till the central chamber.

Compared with the Rigamonti and Tagliani apparatus the present apparatus presents the following differences and advantages: In the Rigamonti and Tagliani apparatus the fabric 110 undergoes only one immersion before the steaming, and during the latter it is sprinkled by the lye in the chamber. This lye becomes charged with the impurities of the fabric, and if it is not changed or removed or partially 115 renewed the fabric will be impregnated with the same impurities; but if the lye is often changed a great and still useful part thereof is lost. In my improved apparatus the lixiviation takes place in a perfectly systematic 120 manner and only the completely-exhausted lye is thrown away, while, on the other hand, the final lixiviation is effected with an absolutely pure and caustic lye.

My improved apparatus presents over both 125 examples above described the great advantage of working at a higher pressure and presents also the greater advantage of a methodical lixiviation, which permits of utilizing all the alkali employed. The methodical steam- 130

ing permits of passing gradually from the exterior temperature to the high temperature of the central chamber. The methodical washing permits of passing gradually from the high temperature of the central chamber to the external temperature, and it may be observed that the methodical washing, although already used in some arrangements, has not been used in combination with intermediate steaming in bleaching proceedings or apparatus.

Having thus described my invention and in what manner the same is to be performed, I declare that what I claim, and desire to secure by Letters Patent, is—

1. In an apparatus for treating fabrics, the combination of a casing provided with partitions so arranged that said casing is divided into chambers which may be separated from each other by liquid seals, means for introducing steam under pressure into each of said chambers, means for introducing a bleaching agent in the chambers on one side of the central chamber, and means for introducing washing agents in the chambers on the other side of the central chamber, the parts being so arranged that the washing and bleaching agents circulate in the reverse direction to that of the fabric under treatment and that the fabric after entering the casing shall be subjected to successively-increasing pressures of steam until a maximum is reached and then to successively-decreasing pressures of steam, substantially as described.

2. In an apparatus for treating fabrics, the combination of a casing provided with partitions forming chambers adapted to be separated from each other by liquid seals, means for supplying steam under pressure to each of said chambers, means for supplying a liquid bleaching agent under pressure to the chambers on one side of the central chamber, and means for supplying a washing agent under pressure to the chambers on the other side of the central chamber, the steam-pressure in the central chamber being the highest and the arrangement being such that the internal pressure is balanced by several liquid columns arranged parallel with each other, the collective height of which columns is equal to the height of a single liquid column that would balance the steam-pressure in the central chamber, substantially as described.

3. In an apparatus for treating fabrics, the combination of a casing provided with upwardly and downwardly extending partitions which divide said casing into chambers adapted to be closed by liquid seals, means for supplying steam under pressure to each of said chambers, means for supplying a bleaching agent under pressure to the chambers on one side of the central chamber, means for supplying a washing agent under pressure to the chambers on the other side of the central chamber, the steam-pressure being highest in the

central chamber and decreasing successively toward either end of the apparatus, and means for causing the fabric under treatment to pass into said casing through said chambers successively and out of said apparatus, whereby the fabric is subjected first to the action of the most impure part of the bleaching agent, then to a pressure of steam, then to a purer part of the bleaching agent, then to an increased pressure of steam and so on until the fabric passes out of the bleaching agent into the central chamber in which the pressure of steam is the highest, then passing through the washing agent at the point where it is most impure, then passing through steam under a pressure less than that of the central chamber and so on, and finally passing out through the purest part of the washing agent and under the least pressure into the atmosphere, substantially as described.

4. In an apparatus for treating fabrics, the combination of a casing provided with upwardly and downwardly projecting partitions which overlap each other forming chambers adapted to be closed by liquid seals, means for introducing steam under pressure to each of said chambers, means for introducing a bleaching agent under pressure to some of said chambers and means for introducing a washing agent under pressure to others of said chambers, substantially as described.

5. In an apparatus for treating fabrics, the combination of a casing provided with reversely - arranged overlapping partitions forming chambers adapted to be closed by liquid seals, means for introducing steam under pressure into each of said chambers, means for causing a washing agent to circulate under pressure through the chambers at one end of said apparatus, means for causing a bleaching agent to circulate under pressure in the chambers at the other end of said apparatus, and means for causing the fabric under treatment to travel through said chambers in a direction opposite to the direction of the circulation of the washing and bleaching agents, substantially as described.

6. In an apparatus for treating fabrics, the combination of a casing provided with reversely - arranged overlapping partitions forming chambers adapted to be separated from each other by liquid seals, means for supplying steam under a comparatively high pressure to the central one of said chambers, means for supplying steam under successively-decreasing pressures to each of the chambers arranged on either side of said central chamber, means for supplying a bleaching agent under pressure to form a liquid seal between said central steam-chamber and the chamber next thereto, means for supplying a washing agent under pressure to the outermost one of said chambers arranged on the other side of said central chamber, connections whereby said bleaching and washing agents are caused

to travel from the chambers in which they are first introduced away from and toward said central chamber respectively, and means for causing the fabric under treatment to pass 5 through said chambers successively in a reverse direction to the circulation of the bleaching and washing agents, substantially as described.

7. In an apparatus for treating fabrics, the combination of a casing provided with reversely - arranged overlapping partitions forming chambers adapted to be separated from each other by liquid seals, means for supplying steam at successively - increasing pressures to a number of said chambers, means for supplying a bleaching agent under pressure to form liquid seals between said chambers and to cause said bleaching agent to circulate under pressure from the chamber subjected to the greatest steam-pressure to chambers subjected to a less steam-pressure successively, and means for causing the fabric to pass through said chambers whereby said fabric is subjected first to the most impure part 25 of the bleaching agent, then to a comparatively low pressure of steam, then to a purer part of the bleaching agent, then to a higher pressure of steam and so on until the fabric passes entirely out of the bleaching agent 30 whereupon it is subjected to the highest pressure of steam, substantially as described.

8. In an apparatus for treating fabrics, the combination of a casing provided with reversely - arranged overlapping partitions forming chambers adapted to be separated from each other by liquid seals, means for supplying steam under pressure to some of said chambers, the pressure in said chambers diminishing successively from one to the other, 35 and means for supplying a washing agent under pressure to all of said chambers except one in which chamber the steam-pressure is

the highest, and means for causing the fabric under treatment to travel through said chambers whereby said fabric is subjected first to 45 the highest steam-pressure, then to the action of the most impure part of the washing agent, then to a less steam-pressure, then to a purer part of the washing agent, and so on until the fabric finally emerges from the casing, substantially as described.

9. In an apparatus for treating fabrics, the combination of a casing provided with reversely - arranged overlapping partitions forming chambers adapted to be separated 55 from each other by liquid seals, means for supplying steam under pressure to each of said chambers, the steam-pressure being greatest in the central chamber and diminishing gradually and successively in the chambers 60 on either side thereof, means for supplying a bleaching agent under pressure to one of the chambers next adjoining the central chamber, pipes communicating with the top of the liquid seal in one chamber with the bottom 65 of the liquid seal in the next succeeding chamber, means for supplying a washing agent under pressure to the outermost of the chambers arranged on the other side of said central chamber, connecting-pipes and pumps connecting 70 said chambers containing the washing agent, inlet and outlet pipes for supplying the bleaching and washing agents to said casing, rollers arranged near the top and bottom of said casing for guiding said fabric, and 75 loopers located in some of said chambers, substantially as described.

In testimony whereof I affix my signature in presence of two witnesses.
